UNITED STATES PATENT OFFICE.

JOHN CHISHOLM FRANCIS, OF NEW YORK, N. Y., ASSIGNOR TO ELIAS M. GREENE, OF SAME PLACE.

COMBINED ANNUNCIATOR AND TELEPHONE SYSTEM.

SPECIFICATION forming part of Letters Patent No. 447,768, dated March 10, 1891.

Application filed November 5, 1889. Serial No. 329,293. (No model.)

To all whom it may concern:

Be it known that I, JOHN CHISHOLM FRANCIS, a subject of the Queen of Great Britain, residing at New York, in the county and State of New York, have invented certain new and useful Improvements in a Combined Annunciator and Telephone System, of which the following is a specification.

The object of my invention is to provide a combined annunciator and telephone system for use in hotels and other similar places in such a manner that the ordinary annunciator wires or circuits can be used without an expensive change to enable telephonic communication to be held between the office and the various rooms or apartments connected therewith.

My invention consists in the combination and arrangement of the telephone-instruments with the instruments and circuits of the annunciator system, and in the specific arrangement of devices whereby this may be carried out, as more fully explained hereinafter.

In the accompanying drawings, Figure 1 is a diagrammatic representation of the connections between the office and one apartment, and the arrangement of the apparatus necessary to complete the telephonic and annunciator connection. Fig. 2 is a similar representation of a slightly-modified arrangement of circuits, and Fig. 3 is a sectional view of a circuit-breaking telephone-connection which I prefer to make use of. Fig. 4 is an enlarged sectional view of the telephone D.

In the drawings, M represents a main battery, which is shown supplying a single annunciator and telephone circuit; but which, of course, can furnish energy to numerous circuits.

A represents a bell, and B an annunciator-drop arranged in a circuit and located at the office or other central position.

C D are respectively transmitting and receiving telephone instruments, also arranged at the office.

E and F are respectively a transmitter and receiver arranged in one of the rooms or apartments, and G is a push-button or other circuit-controller, also arranged in the apartment. The circuit from the battery passes

through the wire 1, thence by the wire 2 to the push-button, by the wire 3 to and including the annunciator and bell, and by the wire 4 to the binding-post 5 of the transmitter. 55 The wire 6 connects the binding-post 7 of the transmitter to the other pole of the battery M.

Normally the telephones C and D are out of the main circuit including the bell and annunciator, and I prefer to accomplish this in 60 a manner hereinafter described. In a shunt-circuit 8 around the push-button are arranged the transmitter and receiver E F, the shunt-circuit being normally open, as hereinafter explained. With this arrangement closing 65 the circuit at the push-button G operates the bell A and the annunciator B at the office and gives notice that the occupant of the apartment desires to communicate with the office. 70

In Fig. 2 the circuits are practically the same, except that instead of the main circuit normally passing from the bell to the telephone-instruments it goes through the frame, drop, spring contact-piece, and the coils of 75 the annunciator, and thence through the bell-magnet and by the wire 9 to the battery, and the office telephones C D are in a normally-open branch circuit 10, connected to one pole of the battery and terminating in a bar H 80 common to all the annunciators, so that when any annunciator-drop falls the circuit through the annunciator is broken, and the branch circuit 10, through the telephones C D, is closed by the annunciator-drops falling on the bar 85 H, and the annunciator and bell are cut out of circuit and the telephone-instruments C D are included in the main circuit.

In Fig. 3 I have shown a telephone-instrument of the construction I prefer to use in 90 the apartment, consisting of an ordinary magneto-telephone having the coil I provided with a loop J, the terminals of which are in the form of springs K. Mounted in the end of the handle of the telephone is a hook L, the 95 end of which normally extends between the free ends of the springs K and closes the circuit through the telephone, being held in this position by a spring N surrounding the inner portion of the hook. When, however, the 100 hook is partially withdrawn, as by hanging the telephone upon the hook, the circuit is

automatically broken at the terminals K, the weight of the telephone overcoming the tension of the spring N. It will thus be seen that the telephone F in the apartment, being 5 of the construction shown in Fig. 3, when hanging upon the hook e normally opens the circuit through the conductor S, so that normally the circuit in the apartment is open both at the push-button and at the telephone-instruments. 10 When, however, the telephone F is removed for the purpose of communicating with the office, the circuit through the telephones E and F is automatically closed.

The telephone D at the office may be constructed like the telephone shown in Fig. 3 or not, but should be provided also with an unbroken electric connection through the handle and the hook L, and I have accomplished this by means of the branch 11, leading 15 from the ordinary conductor 12, which includes the magnet-coil 13, and extending to and connected with the hook L, and the support O is connected electrically with the binding-post 7. Thus constructed, it will be seen that normally the circuit from binding-post 20 5 includes the wire 12, the branch 11, the hook L, the support O, and binding-post 7, cutting out the coil of the magnet of the telephone D and the electrodes of the transmitter, so that the annunciator and bell circuit will not 25 include this unnecessary resistance. When, however, the telephone D is removed from its support O, this short circuit is broken and the telephones C D are included in the main 30 circuit.

In the arrangements of circuits in Fig. 1 the magnets of the bell and annunciator remain in the circuit while the telephones are being used; but as their coils have comparatively low resistance they do not materially interfere with communication; but in the arrangement shown in Fig. 3 these coils are removed from the circuit when the telephones are included and in operation.

45 From the above it will be seen that I am enabled to provide telephonic communication between the various apartments and the office

in addition to the ordinary annunciator communication by making use of the circuits of the annunciator system, and the circuits are 50 so arranged that the telephone-instruments do not interfere with the annunciator system, and when desired the annunciator system may be removed from the circuits of the telephone-instruments. 55

What I claim as my invention is—

1. The combination, with an annunciator system including the battery, a normally-open push-button in the apartment, an annunciator and bell at the central office, and a branch 60 circuit from the battery including the telephone-instruments, said branch circuit terminating in a bar, of telephone-instruments located in the apartment in a normally-open branch around the push-button, whereby 65 when the push-button is closed the bell and annunciator will be operated and the drop of the annunciator will automatically close the circuit through the telephones at the central office and cut out the annunciator and bell, 70 substantially as described.

2. A telephone-instrument the coil of which is provided with a loop connected to spring-terminals having a spring-actuating hook normally closing the terminals and arranged 75 to break the circuit at the terminals when supporting the telephone, substantially as described.

3. The combination, with an annunciator system, of circuits, telephone-instruments included in said circuits, a support connected to one of the terminals of a telephone, a hook connected with one of the telephone-instruments, and a branch circuit around the coil of the telephone and including the hook and 80 the other terminal of the telephone, substantially as described.

In testimony whereof I have signed my name to this specification in the presence of two subscribing witnesses.

JOHN CHISHOLM FRANCIS.
